UNITED STATES PATENT OFFICE.

JOHN W. PLUNKETT, OF DUNSTALL PRIORY, COUNTY OF KENT, ENGLAND.

APPARATUS FOR BURNING GAS.

SPECIFICATION forming part of Letters Patent No. 280,666, dated July 3, 1883.

Application filed February 26, 1883. (No model.) Patented in England December 23, 1882, No. 6,142.

To all whom it may concern:

Be it known that I, JOHN WILLIAM PLUNKETT, a subject of the Queen of Great Britain and Ireland, and residing at Dunstall Priory, 5 in the county of Kent, England, have invented certain Improvements in Gas Ovens, Stoves, &c., (for which I have obtained a British patent, No. 6,142, December 23, 1882,) of which the following is a specification.

10 My invention consists of the combination, with a gas stove or oven, of a device whereby the supply of gas is automatically admitted when the door of the stove or oven is opened and is automatically shut off again when the 15 door is closed, before the gas is ignited or when the gas is accidentally extinguished, as more fully described hereinafter.

In the accompanying drawings, Figure 1 is a side view of a gas-stove with my improvements applied thereto, and Fig. 2 a sectional plan of the same.

The supply-pipe *g* for the gas is secured to the outside of the stove or oven in any convenient position, and is provided with a cock, 25 *h*, having a lever, *i*, connected to a vertical weighted rod, *n*, adapted to slide in guides on the side of the oven. The gas-supply pipe *g* passes to the interior of the oven, and is there perforated for the issue of the gas-jets, as indicated by dotted lines in Fig. 1.

The hinged door *l* of the oven or stove is provided with an inclined or cam-like projection, *p*, adapted as the door is opened to act on the short arm of a lever, *q*, pivoted to the 35 side of the oven or stove, so as to raise the long arm of the said lever. This in turn acts on the weight or projection *n*, secured to the vertically-sliding rod *n*, so as to raise the said rod, and thus open the cock *h* to admit the supply of gas to the interior of the stove or oven as the door *l* is opened.

Within the interior of the stove or oven is an expansion-bar, *k*, secured at one end to the casing of the oven and at the other pivoted to 45 the lever *j*, which in turn is pivoted to the frame at *j*, and has connected to it a second expansion-rod, *k*, free to slide in a guide, and carrying a projection, *k*, extending through a slot to the outside of the casing at the lower 50 end of the vertical rod *n*.

When the gas-burners within the stove or oven are not lighted, the bars *k* being in their normal state, the projection *k* is out of the line of the rod *n*; but when the door *l* has been opened, and the valve *h* thus opened, and the 55 jets within the casing ignited, the bars *k* expand, so as to bring the projection *k* below the rod *n*, the door *l* having been meanwhile kept open. When the door is now closed, the rod *n* will rest on the projection *k* and keep 60 the valve *h* open, as shown in Fig. 1; but should the lights be extinguished the contraction of the bars *k* will withdraw the projection *k* from below the rod *n*, allow the latter to drop, and close the cock *h*.

Instead of combining a projection, *p*, on the door with a lever, *q*, to operate the valve, the door *l* may be arranged to act on a sliding wedge-shaped or inclined bar, so as to raise the rod *n*, for the purpose described. Instead 70 of having two expansion-bars, *k*, with an intermediate lever, one bar may in some cases be sufficient, and in place of the bar a device consisting of a combination of metals acting on the compensating chronometer-balance system, or as the expander in a pressure-gage, may be employed.

I claim as my invention—

1. The combination of the supply-pipe of a gas stove or oven having a cock with a door 80 and intermediate devices, substantially as described, whereby on the opening of the door the said cock will be opened.

2. The combination of the supply-pipe of a gas stove or oven having a cock, *h*, lever *i*, 85 and rod *n*, with the door and intermediate devices to act on said rod, substantially as and for the purpose set forth.

3. The combination of the supply-pipe of a gas stove or oven having a cock, *h*, and operating-rod *n*, with a door having an inclined projection, *p*, and lever *q*, substantially as described.

4. The combination of the supply-pipe of a gas stove or oven having a valve, *h*, and operating-bar *n*, with an expansion-bar within the oven, and having a projection adapted to come within range of said rod *n* when the said bar is expanded.

5. The combination of the supply-pipe of a 100

gas stove or oven having a valve, *h*, and operating-rod *n*, with expansion-bars *k* *k'* and pivoted lever *j* within the casing, the bar *k'* having a projection, *k²*, extending to the outside 5 of the casing, substantially as and for the purpose set forth.

In testimony whereof I have signed my name

to this specification in the presence of two subscribing witnesses.

JOHN W. PLUNKETT.
